UNITED STATES PATENT OFFICE.

WILLIAM F. ROBERTS, OF KELLOGG, IDAHO.

DESIGN FOR A WRENCH.

54,127.

Specification for Design.

Patented Nov. 4, 1919.

Application filed May 17, 1919. Serial No. 297,970. Term of patent 7 years.

To all whom it may concern:

Be it known that I, WILLIAM F. ROBERTS, a citizen of the United States, residing at Kellogg, in the county of Shoshone and State of Idaho, have invented a new, original, and ornamental Design for Wrenches, of which the following is a specification, reference being had to the accompanying drawing, forming a part thereof.

Figure 1 is a face view of the wrench embodying my new design.

Fig. 2 is an edge view thereof looking in the direction of the arrow.

The features consist in all of the end and

edge wrench notches being disposed on one side edge of the wrench head with the remaining side edge straight and unbroken. The head is provided with cross shaped wrench perforations. The wrench head is flat and the hook end is flat while the intermediate handle portion is cylindrical. The hook projects laterally from the handle on the smooth edge side of the wrench head and opposite from the notch edge side.

I claim:

The ornamental design for a wrench substantially as shown and described.

WILLIAM F. ROBERTS.
